PRINTING PRESS

Emmett F. Kidrick and Walter G. Miller,
Bremerton, Wash.

Application January 11, 1943, Serial No. 471,975

7 Claims. (Cl. 101—212)

(Granted under the act of March 3, 1883, as
amended April 30, 1928; 370 O. G. 757)

This invention relates generally to printing presses and more particularly to a printing press for printing title blocks on tracing cloth, paper or other material of any length.

An object of the invention is the provision in a printing press of a geared impression cylinder operable over racks, and a cam mechanism for raising and lowering the racks and cylinder away from and towards the work.

Another object of the invention is to provide a means whereby the ink roller mechanism is driven by the impression cylinder.

A further object of the invention is to provide a foot operated mechanism for securing a drawsheet, make-ready and packing to the bed.

With the above and other objects in view, the invention consists in the construction, combination and arrangement of parts as will be described more fully hereinafter.

Reference is to be had to the accompanying drawings, forming a part of this specification, in which like reference characters indicate corresponding parts throughout the several views, and in which

Fig. 1 is a perspective view of the impression cylinder and operating mechanism of the printing press,

Fig. 2 is a section on the line 2—2 of Fig. 1,

Fig. 3 is a side elevation of the mechanism for freezing the drawsheet, make-ready and packing,

Fig. 4 is a section on the line 4—4 of Fig. 1,

Fig. 5 is a section on the line 5—5 of Fig. 1,

Fig. 6 is a detailed view of the gripper finger mechanism.

Fig. 7 is a detail showing the inking roller driving mechanism, and

Fig. 8 is an end view of Fig. 7.

Referring more particularly to Fig. 1 of the drawings, the numeral 10 designates the bed of a printing press, preferably constructed of ribbed cast iron milled on the face and cast integrally with side aprons 11 and end members (not shown). The bed is supported by a plurality of legs 12 that are suitably cross-braced to provide stability. The longitudinal sides of the press bed are so formed as to provide an angled connection with the aprons, and in these angles 13 are seated toothed racks 14 along which a form cylinder 15 travels, as will be explained hereinafter. Dowel pins 16 (Fig. 5), mounted in the horizontal faces of the angles, prevent longitudinal movements of the racks along the angled bed and aprons, but permit their vertical movement so that the cylinder movable therealong may be

raised from the printing press bed. Suitable guides 17 (Fig. 1) positioned along and secured to the aprons further assist in maintaining the racks in proper parallelism.

The form cylinder 15 is preferably hollow and may be of any desirable size, although it has been found that fourteen inches in diameter and forty inches in length are the optimum dimensions for the class of work for which the press is designed. The cylinder is webbed inside at three points throughout its length and is closed at the ends by welded discs. Geared wheels 18 are bolted to the end discs and engage with the racks 14 for movement of the cylinder therealong, and in this movement the cylinder is guided against axial displacement by flanged wheels 19 bolted through the geared wheels 18 to the ends of the cylinder, these flanged wheels riding on guide rails 20 attached to the racks 14 from the under sides by counter-sunk bolts (not shown). By referring more particularly to Fig. 5, it will be noted that the racks 14 themselves are L-shaped, and that the rails 20, which have their upper outer sides slightly bevelled to receive the flanges on the wheels 19, are seated on the horizontal portions of the L-shaped racks. The form cylinder is propelled along the racks by cranks 21, one at each end of the cylinder, the cranks being keyed to a shaft 22 extending through and suitably attached to the cylinder so that the two members will turn together. The shaft is supported in bearings 23 carried by standards 24 positioned near the ends of the cylinder. The form cylinder is cross-scribed in any desired manner at regular intervals so that a metal or rubber printing plate 25 may be accurately adjusted on the cylinder. Stops 26, that may be adjustable along or fixed at proper places on the racks 14, prevent the form cylinder from overrunning the racks.

The standards 24 support two composition inking rollers 27 and a hollow oscillating ink distribution roller 28, all of which are mounted in adjustable bearings 29 at each end of the shafts 30 for the inking rollers and shaft 31 for the distribution roller. The inking rollers derive their rotation through expansion rings 32 thereon engaging with frictional bands 33 carried by the cylinder, and rotary motion is imparted in turn to the distribution roller through the expansion rings 32. The oscillatory movement of the distribution roller is obtained by means of a cam 34 positioned at each end of the roller engaging with stationary cam followers 35 attached to brackets 36 secured to the standards

24, as may be seen more clearly in Fig. 2. If it is desired to move the distribution roller at times when the cylinder is not being operated to obtain additional or a more evenly distribution of ink over the inking rollers, it may be turned by hand through a crank 37 secured to the shaft 36. Also, there is provided a ball 38 with hand grips 39 so that the distribution roller may be carried about or wiped over an inking pad without soiling the hands.

The standards 24 are held in proper spaced relation by two lower tie-rods 40 and an upper tie-rod 41, the latter being more clearly seen in Fig. 2. The lower tie-rods have their ends mounted in arms 42 that may be made integral with or attached in any suitable manner to the standards 24, whereas the upper tie-rod is connected to the standards by nuts 43. Rollers 44, mounted on the lower tie-rods 40 and which are operable over the upper surface of the guide rails 20, support the weight of the impression cylinder assembly, and are so positioned with respect to racks 14 that positive engagement will be maintained at all times between the geared wheels 18 and the racks. By this arrangement, the form cylinder is easily moved, yet slipping of the cylinder when in operation is reduced to a minimum.

In the drawings the form cylinder and paper 45, secured under gripper fingers 46 are positioned for the impression revolution with the racks 14 tight in their seats in angle 13. At the end of this impression revolution the cylinder is raised preparatory to its return or non-impression revolution. This lifting or raising is accomplished by a mechanism, the details of which are more clearly shown in Fig. 4. A crank or lever 47 operates two parallel shafts 48, one below each end of the press bed, that are connected to oscillate simultaneously by rods 49 having a pivotal movement in one end of links 50, the other ends of which are fixedly secured to the shafts 48. Cam followers 51 have one end riding over cams 52 mounted to turn with the shafts 48, and the other end engaging with the under side of the racks 14, so that as the full sides of the cams are uppermost the followers will urge the racks upward, freeing the form cylinder from the now printed paper. It is to be understood that there are to be cams and followers at each end of the shafts 48 to insure equal raising of the racks, and that there are other shafts and cams intermediate of those illustrated, if it is desired. Thus, by turning the crank or lever 47 in the appropriate direction the racks 14 may be raised or lowered, as the case may be, to be guided in movement by the dowel pins 16, as previously stated.

The cylinder now being raised, it is started on its return or unimpression revolution. As it approaches the starting point of its impression revolution the rear one of the rods 49 (or left one as the drawings are viewed) contacts with and raises a finger 53 (Fig. 6) fixedly secured to a shaft 54 mounted in bearings 55 to raise the gripper fingers 46 freeing the printed paper. A coil spring 56 is suitably attached to the shaft and one of its bearings urges the gripping fingers to normally exert pressure on the paper to hold it against disarrangement during the printing operation. A hand grip 57 is attached to the shaft 54 so that the gripper fingers may be manually moved.

In Fig. 3 there is shown a mechanism for holding down the drawsheet, make-ready and packing during the printing operation. Extending lat-

erally across upper surface of the bed of the press there are two arcuate shaped grooves 58 into which are placed the ends of the drawsheet, make-ready and packing, shown in the drawings 5 as a unit 59. Spring depressed clamp-bars 60 fit into the grooves and firmly hold the unit therein. When seated in operative position in the grooves, the upper surfaces of the clamp bars should be flush with the top surface of the unit 10 to eliminate uneven surfaces for the paper to rest on. When it is desired to remove the unit, the machine operator steps on foot pedals 61, fulcrumed in supports 62, conveniently placed on the floor under the press. These pedals operate lift bars 63 pivotally connected to arms 64 secured to shaft 65 journaled in the guides 17. The arms 64 contact with and raise clamp bar pins 66 against the pressure of springs 67. Of course, when pressure is removed from the 15 pedals, the springs restore all parts to their normal position.

It will be seen from the above description that there has been provided a printing press particularly adapted to print the title block on paper 25 of any length used by draftsmen. While the invention has been designed and described as a title block printer, it is to be understood that its use need not be restricted to this type of printing, as its possibilities are limited only to the 30 format of the printing plate attached to the form cylinder.

It will be understood that the above description and accompanying drawings comprehend only the general and preferred embodiment of 35 our invention and that various changes in details of construction, proportion and arrangement of parts may be made within the scope of the appended claims and without sacrificing any of the advantages of our invention.

40 The invention described herein may be manufactured and used by or for the Government of the United States for governmental purposes without the payment to us of any royalty thereon.

What is claimed is:

1. In a printing press, in combination, a stationary bed, a form cylinder movable over the bed, elevatable racks on which the cylinder moves, guide rails on said racks, a frame supporting said cylinder and movable on said guide rails, and means for elevating the racks.

2. In a printing press, in combination, a stationary bed, a form cylinder movable over the bed, raisable racks on which the cylinder moves, geared wheels carried by the cylinder and engaging with the racks, guide rails on said racks, a frame movable on said guide rails having bearings supporting said cylinder, and means for raising the racks to change the cylinder from an impression to a non-impression position.

60 3. In a printing press, in combination, a stationary bed, a form cylinder movable over the bed, elevatable racks on which the cylinder moves, guide rails supported by the racks, a supporting frame for the cylinder movable along the guide rails, means for manually elevating the racks to raise the cylinder to a non-impression position.

4. In a printing press, a stationary bed, sprongs at the sides of the bed connected thereto by right angled portions, gear racks mounted in these angled portions and having a right angled groove along their outer edges, guide rails mounted in said grooves, cam followers extending through bores in the horizontal faces of the angled portions connecting the sprongs to the bed, cam-shafts mounted through the sprongs below the

bores, cams on said shafts coacting with the cam followers, hand-operated means for actuating said shafts to raise and lower the racks.

5. In a printing press as claimed in claim 4, dowel pins mounted rigidly in the horizontal faces of said angled portions slidable in corresponding bores in said racks to guide them vertically while being raised and lowered.

6. In a printing press, a stationary bed, clamping means for clamping the edges of work sheets on the bed comprising cylindrical grooves running across the bed, correspondingly shaped bars mounted on pins passed through bores in the

bottom of said grooves, spiral springs about said pins compressed between the ends of said pins and the bottom of the bed for holding said bars resiliently within said grooves, foot-operated means acting against the bottom of said pins to raise the clamping means and release the sheets.

7. In a printing press, means as claimed in claim 6 wherein the foot-operated means comprise a foot-operated lever, a rod pivotally connected thereto and also pivotally connected at its other end to lever means for raising said pins.
